UNITED STATES PATENT OFFICE.

JOHN BURROWS HALL TRAINER, OF WILLIAMSPORT, PENNSYLVANIA.

DESIGN FOR A GAME-BOARD.

SPECIFICATION forming part of Design No. 26,168, dated October 6, 1896.

Application filed July 14, 1896. Serial No. 599,194. Term of patent 31 years.

To all whom it may concern:

Be it known that I, JOHN BURROWS HALL TRAINER, a citizen of the United States, residing at Williamsport, in the county of Lycoming and State of Pennsylvania, have invented and produced a new and original Design for Puzzle or Game Boards, of which the following is a specification, reference being had to the accompanying drawing, forming a part thereof, said drawing being a plan view of my puzzle or game board.

The leading feature of my invention consists in a board A, which is rectangular in form and square, and said board is provided centrally with the picture or representation of a chair, as shown at B, around which is a shield C, or said chair or the picture thereof is placed on the picture or the representation of the shield, and arranged around the shield and chair in the form of a square are eight spaces D, which are represented by circles, and inclosing the square thus formed and near the edges of the board are eight other spaces, which are also represented by circles, one of which is placed at the corner of the board and one about midway of each side, and the corner-spaces E and D are connected by diagonal lines G, which extend from the cor-

ners of the board to the shield C, and the central spaces D and E are connected by transverse lines H, which also extend to the central shield.

The design thus produced is regular and symmetrical in form and attractive to the eye. The principal features of said design consist in the arrangement of the spaces D and E, the shield C, and the chair B, and additional spaces D and E may be provided without essentially changing the design, the only requirement in this connection being that said spaces be arranged, as shown, in the form of a square.

Having fully described my invention, I claim as new and desire to secure by Letters Patent—

The design for puzzle or game board, herein shown and described.

In testimony that I claim the foregoing as my invention I have signed my name, in presence of the subscribing witnesses, this 9th day of July, 1896.

JOHN BURROWS HALL TRAINER.
